US00D784373S

(12) **United States Design Patent** (10) **Patent No.:** **US D784,373 S**
Cai (45) **Date of Patent:** **** Apr. 18, 2017**

(54) **DISPLAY SCREEN OR PORTION THEREOF WITH GRAPHICAL USER INTERFACE**

(71) Applicant: **LENOVO (BEIJING) CO., LTD.**, Beijing (CN)

(72) Inventor: **Hua Cai**, Beijing (CN)

(73) Assignee: **Lenovo (Beijing) Co., Ltd.**, Beijing (CN)

(**) Term: **14 Years**

(21) Appl. No.: **29/499,904**

(22) Filed: **Aug. 20, 2014**

(30) **Foreign Application Priority Data**

Feb. 21, 2014 (CN) 2014 3 0032079

(51) **LOC (10) Cl.** **14-04**

(52) **U.S. Cl.**

USPC **D14/486**

(58) **Field of Classification Search**

USPC D14/485-495; 715/763, 810, 836, 837, 715/846, 847, 977

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the office upon request and payment of the necessary fee.

The FIGURE is a front view of a display screen or portion thereof with graphical user interface showing our new design.

The broken lines showing a display screen illustrate portions of the article and form no part of the claimed design.

1 Claim, 1 Drawing Sheet
